John W. Thompson
his ATTORNEY

UNITED STATES PATENT OFFICE.

THOMAS RALPH GOLDSMITH, OF ERIE, PENNSYLVANIA, ASSIGNOR TO AMERICAN METER COMPANY, INCORPORATED, OF NEW YORK, N. Y., A CORPORATION OF DELAWARE.

METER.

Application filed January 29, 1926. Serial No. 84,696.

The present invention relates to an improvement in meters and more particularly to mechanism therein for preventing reversal of the indicating and recording devices to 5 fraudulently reduce the reading thereof. It is well known that meters have heretofore been provided with devices for a similar purpose. In one type a stop is interposed in the path of the tangent arm and arranged 10 to arrest reverse movement thereof after a predetermined number of reverse revolutions of said arm. This mechanism is more elaborate than its function justifies and one object of the present invention has been to 15 measurably simplify the reverse arresting devices in meters without sacrificing sure and effective operation.

One embodiment of my invention is illustrated in the drawings accompanying the 20 present specification and in which

Figure 1 is a top plan view of a tangent arm and of reverse arresting device, and

Figure 2, a side elevation thereof.

Referring to the drawings the usual tangent arm 1 of a well known meter mechanism is mounted on and rotates with a crank 2. A worm 3 is secured to crank 2 and cooperates with a detent 4, one end of which is pivotally secured to an arm 5 of a bracket 30 9 by means of a pivot 6. The free end of the detent has one or more teeth 7 and a stop 8 extending beyond the teeth 7. A lug 10 projecting laterally from the detent 4 extends under arm 5 of bracket 9. The bracket 9 may also have a lug 11 positioned 35 opposite one side of detent 4.

Assuming that the crank 2 will rotate in a clockwise direction as indicated by the arrow in Figure 1 during normal positive 40 meter operation, detent 4 will ride freely on the upper face of said worm, said detent being prevented from moving out of operative position away from the worm by suitable means such as the lug 10 engaging the 45 under side of arm 5.

When the metering movement is reversed, 50 crank 2 will rotate counter clockwise and worm 3 will mesh with the tooth or teeth 7 as the case may be, depending on whether the permissible reverse movement is to be one or more complete rotations of the crank 2. Thereupon the stop 8 will be moved into

binding engagement with the top face of worm 3 thereby stopping rotation of the crank 2.

The detent 4 is loosely mounted on pivot 6 in such a way as to be capable of some lateral deflection, for example to and from the position indicated in dotted lines in Figure 1. When the parts occupy their 60 relative positions in which the crank is locked against rotation, detent 4 will bear laterally against a suitable stop, as 11, on bracket 9 so that the detent 4 will occupy a position substantially radial with respect 65 to the central longitudinal axis of crank 2, as the full line position in Figure 1.

When the meter again operates positively, as when the crank rotates clockwise, the 70 detent will be upset from its locking position and be deflected to the dotted line position, thus releasing the worm from frictional or binding engagement with the stop 8. The detent will then move up to unmeshed or free riding position on the upper 75 face of the worm 3.

I claim as my invention:—

1. In a meter the combination of a crank, a worm mounted thereon, and means positioned to permit continuous movement of 80 said crank and worm in one direction of rotation and to frictionally engage said worm to arrest movement of rotation thereof in the opposite direction.

2. In a meter the combination of a crank, 85 a worm mounted thereon, and a detent positioned to ride freely on said worm during rotation of the crank in one direction and movable into frictional engagement with said worm after a predetermined increment of 90 rotation of the crank in the opposite direction.

3. In a meter the combination of a crank, a worm mounted thereon, and a detent having a toothed portion normally out of meshing engagement with the worm during positive 95 operation of the meter and movable into frictional meshing engagement with the worm after a predetermined increment of reverse operation of the meter.

4. In a meter the combination of a crank, a worm mounted thereon, a detent pivotally mounted adjacent thereto and having a portion of its free end riding on said worm

during positive operation of the meter, and another portion of said free end adapted to frictionally engage and arrest rotation of the worm after a predetermined increment of reverse operation thereof.

5. In a meter the combination of a crank, a worm mounted thereon, a bracket, a worm engaging detent pivotally mounted thereon and having its free end supported by said worm, said free end being deflectable by the worm laterally away from the bracket during positive operation of the meter and toward the bracket into worm movement arresting position after a predetermined increment of reverse operation thereof.

10. In a meter, the combination of a crank, a worm mounted thereon, a bracket and a worm engaging detent mounted on said bracket, and means interposed between the 15 detent and the bracket to limit the extent

of movement of said detent in a direction away from said worm.

7. In a meter, the combination of a crank, a worm mounted thereon, a bracket and a worm engaging detent pivotally mounted on 25 said bracket and having a laterally extending lug engaging a portion of the bracket to limit the extent of longitudinal movement of said detent with respect to said worm.

8. In a meter, the combination of a crank, a worm mounted thereon, a bracket, and a worm engaging detent mounted on said bracket and having its worm engaging end deflectable laterally by said worm into and out of frictional motion arresting engagement therewith.

30 In testimony whereof, I have signed my name to this specification this 26th day of Jan., 1926.

T. RALPH GOLDSMITH.
